UNITED STATES PATENT OFFICE.

ENOCH SHENTON, OF MALDEN, MASSACHUSETTS.

DESIGN FOR A HOT-AIR-REGISTER FRONT.

SPECIFICATION forming part of Design No. 18,435, dated July 3, 1888.

Application filed May 31, 1888. Serial No. 275,655. Term of patent 7 years.

To all whom it may concern:

Be it known that I, ENOCH SHENTON, a citizen of the United States, residing at Malden, in the county of Middlesex and State of Massachusetts, have invented and produced a new and original Design for a Hot Air-Register Front, of which the following is a specification, reference being made to the accompanying drawing, in which is represented a front elevation of my newly-designed register-front.

The leading feature of my design consists in the open fret-work figure A, in the shape of a Maltese cross, which is located at and forms the central portion of the register-front, as represented in the accompanying print. The bars forming the arms of the cross A are intersected by a ring, b, concentric with the smaller ring, c, which forms the center of the cross. At the corners of the cross A are four rings, d, which serve to connect the said cross with the longitudinal bars e e, the cross being further connected with said bars e e and with the transverse bars f f by intertwined scrolls g h, these devices forming the inner field of

the design. Outside the bars e e, and between said bars and the border frame B, are serpentine figures i i, which connect the ends of the upper and lower bars f f, the bends of the serpentine figures being connected alternately with the border-frame and the bars e e by short horizontal bars k, between which are pointed or V-shaped studs m.

I claim—

The design for a register-front, comprising the central figure, A, having the form of a Maltese cross, with its concentric rings b c, the corner rings, d, the scrolls g h, the bars e f, and the serpentine figures i i, joined to the sides of the border-frame by the short bars k, with the intermediate pointed studs, m, as herein shown and described.

Witness my hand this 28th day of May, A. D. 1888.

ENOCH SHENTON.

In presence of—

P. E. TESCHEMACHER,
HARRY W. AIKEN.
